VOLUME CONTROL FOR RADIO AMPLIFIER CIRCUITS

Filed July 15, 1927

UNITED STATES PATENT OFFICE

ORIN E. MARVEL, OF DAYTON, OHIO, ASSIGNOR, BY MESNE ASSIGNMENTS, TO GENERAL MOTORS RADIO CORPORATION, OF DAYTON, OHIO, A CORPORATION OF OHIO

VOLUME CONTROL FOR RADIO AMPLIFIER CIRCUITS

Application filed July 15, 1927. Serial No. 206,068.

The present invention relates to improvements in the arrangement and connections of the circuits of an electrical apparatus adapted for the generation, reception or 5 transmission of electrical current oscillations of varying frequencies.

One object of this invention is to provide in an apparatus of the above type a single control which is connected to a plurality of 10 circuits to regulate the volume of the signal produced, the arrangement being such that the volume of the signal may be regulated when receiving signals from either distant or nearby sources without interfering with 15 the quality of the signal.

Further objects and advantages of the invention will be apparent from the following description when taken in connection with the accompanying drawings illustrating one 20 embodiment of the present invention in which

Fig. 1 is a circuit diagram of a radio receiving apparatus of my invention; and

Fig. 2 is an enlarged circuit diagram 25 showing the essential features of a part of Fig. 1.

The apparatus selected as illustrative of my invention is a radio receiving set having an untuned antenna circuit adapted to receive signal current oscillations of different frequencies, to which circuit there are connected in cascade a series of electron devices or audions indicated by the reference characters 21, 22, 23, 24, 25 and 26 respectively. 30 Each of the discharge devices comprises, in the embodiment shown in Fig. 1, a cathode 30, a plate electrode or anode 31, and a grid electrode 32 interposed between the cathode and the anode. Each discharge device or audion is also provided with a heated filament 33 which is connected to a suitable source as the alternating current source 34 to maintain the cathode at the proper temperature for efficient operation.

As illustrated, the audions 21, 22 and 23 function as radio frequency amplifiers, 24 as a detector, and 25 and 26 as audio frequency amplifiers. The filaments 33 of the audions are connected to the common source of current 34 or to any other suitable source of

current, and the cathode elements 30 are interconnected through a connection 35 which is connected to the common ground wire 36 through a condenser 37.

The radio frequency amplifiers 21, 22 and 23 are coupled together and to the detector 24 by means of suitable radio frequency transformers 40, 41 and 42 respectively, each having suitable inductively coupled primary and secondary windings. The detector 24 and the audio frequency amplifiers 25 and 26 are coupled together by means of the two audio frequency transformers 43 and 44. The grids 32 of the audions 22 to 26 inclusive are each connected with the secondary windings of the next proceeding transformers, whereas the grid electrode of the first audion 21 is connected to the antenna circuit, preferably by means of the close coupling of the type illustrated.

The plate electrodes 31 of the audions 21 to 25 inclusive are each connected with the primary windings of the transformers or couplings by which these audions are coupled to the succeeding audions, while the plate of 75 the audion 26 is connected through a suitable translating device such as a loud speaker 48, with a suitable source of current. As illustrated said plate circuits are connected with suitable sources of energy of the proper potential, the plate circuits of audions 21, 22 and 23 being interconnected at the point 49 and connected through a resistance with the positive terminal B+ of the source or B battery 50 as indicated at 53. The negative 80 terminal B- of the B battery is connected through the C battery 51 to the ground 52, which as previously explained is connected through the condenser 37 to the common cathode connection 35 to complete the plate 90 circuits. The plate circuits of detector tube 24 and of the audio amplifiers 25 and 26 are connected with the B battery 50 as indicated at 54, 53 and 55 respectively, so that the proper voltage will be supplied to these 95 various audions.

The grid circuits of each of the audions 21 to 26 inclusive are connected through the C battery 51 to the common cathode wire 35 so that suitable negative potentials are im- 100

pressed upon the grids of the amplifiers 25 and 26. As shown one of the radio frequency tubes has its output circuit controlled by a switch 46 which may be manually closed to 5 place a reactance 47 across the transformer winding.

The grid circuits of the radio frequency amplifiers 22, 23 and 24 are each provided with an adjustable capacity 58 in parallel 10 with the transformer secondaries so that these circuits may be adjusted to resonance with the incoming signal oscillations to be amplified; and the grid circuit of the detector tube 24 is also provided with the condenser 15 and grid leak elements 57 customarily employed in the grid circuits of detector tubes. In the apparatus set forth in Fig. 1, the tuning condensers 58, which are connected across the secondary windings of the transformers 20 40 and 41, are also provided with balancing plates 59 connected to the proper point 60 of the next succeeding transformer secondary so that a suitable amount of energy may be fed back from the succeeding grid circuit 25 opposing the energy in the proceeding grid circuit to maintain these grid circuits at a substantially constant or negligible effective resistance as set forth in my prior application Serial Number 205,739, filed July 14, 30 1927, entitled Electrical apparatus.

The plate 31 of the audio frequency amplifier 25 is connected to the primary winding of the audio frequency transformer 44 through a condenser 61 and is also preferably connected to a choke 62 connected across the primary as shown. One side of the primary of this transformer is connected through a wire 63 to one end 64 of a potentiometer or resistance 65. This resistance is provided with an 40 adjustable contact 66 which may be moved along the length of the resistance and which may be manually adjusted as desired. This movable contact 66 is connected through the wire 67 to the other side of the primary winding of the transformer 44 so that by moving the contact to the left (see Fig. 1), a low resistance shunt path is provided across the primary of this transformer to control the volume of signal supplied to the transformer 45 and consequently to control the volume of the signal received in the speaker 48. When the contact 66 is moved to the right to the end of the resistance 65 the shunt path across the primary of the transformer will be of sufficiently 50 high resistance so that the power supplied to the transformer from the plate will not be materially affected. The resistance of the element 65 is preferably of the order of about 20,000 ohms (as distinguished from one of several million ohms), so that when the 60 full resistance is applied across the primary of the transformer the latter may operate at substantially its maximum efficiency.

The potentiometer or control resistance 66 65 is also utilized to vary the potential of the

plates or anodes of the radio frequency tubes 21, 22 and 23 which are connected at point 49 to the end 70 of resistance element 65. The variable contact 66 which is connected to one side of the winding of the transformer 70 44 is also connected by the wire 71 to the positive side of the B battery 49. A variable resistance is thus interposed between the positive side of the B battery and the plates of the radio frequency tubes. When the adjustable contact 66 is closely adjacent the end 70 the resistance interposed between the B battery and the tube plates will be a minimum and consequently full B battery voltage will be supplied to maintain the potentials of the 80 plates of these tubes at a proper high value so that they may operate at their maximum efficiency. However, when the adjustable contact 66 is moved toward the end 64 of the resistance the full resistance of the element 85 65 will be in series with the battery connection to the plates of the radio frequency tubes and the potential of the plates will thus be lowered so that the output of these tubes is 90 somewhat reduced. The potential of the 95 plates of the radio frequency tubes may thus be lowered to decrease the output of the radio frequency tubes at the same time the output of the audio frequency amplifier 25 is reduced by partially short-circuiting the primary of the transformer 44. On the other hand when the transformer 44 is operating at its full efficiency and the adjustable contact 100 66 is adjacent the end 70 of the resistance the output of the plate circuits of the radio frequency tubes also will be a maximum. By using a resistance of the order of 20,000 ohms it is thus possible to provide for an efficient control of the volume of signal received from either nearby or distant sending stations and 105 such a control is particularly desirable when the electron tubes are energized from an alternating current source since in this case a control of filament current to vary the volume is not easily accomplished. When receiving 110 signals from nearby powerful stations the usual several milliamperes flowing in the plate circuits of the radio frequency tubes may be reduced to several tenths of a milliampere which is sufficient to provide for suitable 115 operation of the radio frequency tubes. The use of a comparatively low resistance potentiometer having a resistance of the order of 20,000 ohms, however, permits the potentiometer to be made in a practical manner so 120 that it may safely carry the several milliamperes required when the plates of the radio frequency tubes operate at their maximum efficiency with full plate voltage applied to them, there being no likelihood of overheating or burning up of the resistance such as might happen if the potentiometer were of several million ohms resistance, it being a difficult or almost impossible matter to manufacture 125 a very high resistance of this nature 130

in small size so that it may carry this amount of current without overheating or burning up.

It is intended that my invention shall be susceptible to use with electron discharge devices such as shown in Fig. 2 in which the cathode is the heated electrode 80 of these tubes. The connections from the resistance 65 to the plates 31 of the radio frequency 10 amplifying tubes 21, 22 and 23 is similar to that shown in Fig. 1, the movable contact 66 being also shown connected to the positive terminal of the B battery 50 and to the primary winding of the audio frequency transformer 44, the latter being connected by the wire 63 to the end 64 of the resistance element. The various connections of the filaments and the rest of the grid and plate circuits have not been indicated in this view and 15 may be of conventional character.

It will thus be apparent that I have provided a single device which may be manually adjusted to suitably regulate the volume of output of a radio apparatus of the character 20 set forth. The common resistance element 65 being connected in the plate circuits of the radio frequency tubes and also connected to place a variable path in shunt with a transformer winding operating at audio frequencies 25 provides for suitable control of the signal in a simple manner.

While the method herein described and the forms of apparatus for carrying this method into effect, constitute preferred embodiments 30 of the invention, it is to be understood that the invention is not limited to this precise method and forms of apparatus, and that changes may be made in either without departing from the scope of the invention which 35 is defined in the appended claims.

What is claimed is:

1. In a radio receiving apparatus, a plurality of separate associated circuits, a transformer winding in one of said circuits, the other circuit including an output electrode of an electric discharge device, a voltage source connected to an adjustable resistance, and connections from said resistance to said transformer winding and said output electrode so 45 that the output of the transformer may be decreased simultaneously with a change of potential of the output electrode.

2. In a radio receiving apparatus, a plurality of separate associated circuits, a transformer connected in one of said circuits, the other circuit being adapted to carry radio frequency currents and including the anode of an electron tube, a voltage source connected to an adjustable resistance device, and 50 connections between said resistance device and said transformer so as to provide a variable resistance shunt for the transformer and a variable resistance in series with said 55 voltage source to cause the anode potential

to be increased simultaneously with increase of the output of said transformer.

3. In a radio receiving apparatus as set forth in claim 2, the said resistance being of the order of 20,000 ohms.

4. In a radio receiving apparatus, a plurality of associated circuits, a transformer in one of said circuits adapted to transform audio frequency oscillations, the other circuit operating at radio frequencies and including the output electrode of an electric discharge device, an operating member, and resistance means operated by said member and connected to said voltage source, transformer, and output electrode so as to simultaneously 70 increase the voltage supplied from said voltage source to said electrode and increase the efficiency of said transformer.

5. In a radio receiving apparatus, a plurality of separate anode circuits, a potential source in one anode circuit, a resistance in said anode circuit in series with said potential source, means for varying said resistance, a transformer associated with the other anode circuit, connections between said transformer and said resistance to provide a variable resistance in shunt with one side of said transformer for decreasing the output of the transformer as the anode voltage in 80 the said one circuit is decreased.

6. In a radio receiving apparatus, an electron tube having a plate circuit adapted to carry radio frequency oscillations, an associated circuit adapted to carry audio frequency oscillations and including one winding of an audio frequency transformer, and volume control means comprising a common variable resistance element connected with both of said circuits.

7. In a radio receiving apparatus, an electron tube having an anode circuit adapted to carry radio frequency oscillations and including a source of potential, an associated circuit adapted to carry audio frequency oscillations and including the primary winding of an audio frequency transformer, a resistance element, one end being connected to the said source of potential, the other end to one side of said winding, and a movable contact for said resistance element connected to the anode and to the other side of the winding of the transformer.

8. In a radio receiving apparatus having a radio frequency anode circuit and an audio frequency transformer circuit, the method of controlling the volume of said apparatus comprising operating a single control member to simultaneously increase the anode voltage while changing the power supplied to a winding of the transformer.

In testimony whereof I hereto affix my signature.

ORIN E. MARVEL.
